SPRING AND MATTRESS SUPPORT FOR
BEDS AND THE LIKE

Ernest H. Anderson, Jamestown, N. Y.

Application January 8, 1948, Serial No. 1,100

1 Claim. (Cl. 5—238)

1

This invention relates to improvements in beds, couches, and the like, and more particularly to a spring and/or mattress support for such structures.

Except for design changes from time to time, little or no improvement in the structure of beds or couches has occurred. That is, today, as for a long period of time, beds and couches have consisted principally of a pair of end boards or members connected by side rails, the side rails being provided with cleats on which to mount a number of transversely disposed spring or mattress supporting slats. In most instances the slats are merely laid in place on the cleats by way of loosely bridging the space between the side rails and serve no other purpose than to provide a loose and generally unreliable support or mounting for a spring and mattress. Furthermore, these slats, when positioned on the cleats, add nothing whatsoever by way of improving the stability or rigidity of the frame of the bed or couch. The hook-like fasteners which are commonly used to connect side rails and end members of a bed may, for a period of time, serve to maintain the bed or couch frame in fairly accurate rectangular form. However, since these hooks and their manner of application are not intended to particularly serve to rigidify the frame, it frequently occurs that in use the frame becomes somewhat twisted and this twisting can, and frequently does, produce such turning of the slats that they drop out of place. For the most part, in structures of this nature, it is only possible to prevent inadvertent displacement of the slats if the spring to be mounted has a close or snug fit with the frame. Under such circumstances it is the rigid frame of the spring that serves to maintain the bed or couch frame in its proper rectangular form. However, even through the use of a closely fitted spring frame, it is still possible for one or more of the loose slats, that support the spring, to become displaced and either let down an end of the spring or place undue strain thereon and on the bed frame as well.

The present invention is primarily directed to a structure that is applicable to any bed or couch frame; that is, any frame that comprises end members removably or permanently connected by side rails. More particularly, the present invention serves both to rigidify a bed or couch frame and as a support for a spring and mattress intended to be mounted in such frame. To this end, there is disclosed a supporting structure that takes the form of a slat intended to be disposed transversely of its ends

2

with shoes that are adapted to rest on cleats forming part of the side rails of the frame. Any given slat is intended to be of a length that is less than the space between the side rails of a frame for which it is intended and the shoes attached thereto rest on the cleats and abut the side rails. Furthermore, the shoes are so fitted to the slat that there can be no twisting, and are of such length as to have a considerable bearing against the side rails, the purpose being to prevent twisting of the slat when once properly positioned in the bed or couch frame. It will be noted that means is provided by which to yieldingly extend the shoes to predetermined limits beyond the ends of the slat. Additionally, the invention contemplates the provision of slats arranged in units of two or more and provided with shoes that, at corresponding ends of the slats, are integral. It will also be evident that the invention provides means by which single slats or slat units may be applied to a bed or couch frame in such manner as to accommodate a spring and mattress in either of two positions.

25 The invention, therefore, has for its particular objects the provision of convenient, inexpensive, readily removable slat structures for bed or couch frames, which structures serve not only to rigidify these frames but also to adequately support a spring and mattress.

30 Other objects and advantages of the invention will be more fully understood from a consideration of the following specification, taken in conjunction with the accompanying drawings; and 35 in which

Fig. 1 is a fragmentary perspective view of a bed or couch with parts broken away to disclose the location and arrangement of a slat structure embodying one form of the present invention;

40 Fig. 2 is a fragmentary enlarged plan view showing a slat and attached supporting shoe in position of use;

Fig. 3 is a view similar to Fig. 2 showing one extreme position of adjustment of a slat and shoe;

45 Fig. 4 is another view similar to Fig. 3 showing the other extreme position of adjustment of the slat and shoe;

Fig. 5 is a greatly enlarged vertical sectional view, taken substantially on the line 5—5 of Fig. 1, and shows the slat in position of use substantially as it appears in Fig. 2;

Fig. 6 is a fragmentary perspective view of the bed frame showing a unit that includes two slats and shoes in position of use;

55 Fig. 7 is an enlarged fragmentary perspective

view, partly in section, showing the slat end and attached shoe;

Fig. 8 is an enlarged plan view showing one of the slat units and a portion of the shoe in position of use; and

Fig. 9 is a transverse vertical sectional view showing the structure of the shoe for a single slat or slat unit when the structure is mounted on the upper edge of the rail.

Referring more particularly to Fig. 1 of the drawings, the reference numeral 10 is employed to generally designate a portion of a conventional bed or couch frame. This frame includes the usual end boards 11 permanently joined to posts 12. Side rails 13 are removably attached, in any conventional manner, to the posts 12, such, for example, as with some form of well known rail hooks (not shown). Each side rail 13 is provided, along its lower inside edge, with a cleat 14. In usual practice, a number of slats are merely set into the bed frame to bridge the space between rails 13, the slat ends resting on the rail cleats 14.

The present invention, as has been indicated above, consists of the provision of a slat 16 with means for mounting it on the cleats 14. In the present disclosure, slat 16 is a rectangular member, produced from any material suitable to sustain a portion of the required load to which structure of this type is normally subjected. The slat is preferably of a length somewhat less than the distance between the side rails 13. As indicated in the drawings, the slat may slightly overhang the cleats 14 when in position of use, but under no circumstances is it intended to be of such length as to even closely approach the side rails 13. Near each end of slat 16 is an opening 17 and, in the present disclosure, since this opening is adapted to receive a bolt 18 having a portion of its shank squared, a portion of the walls of the opening 17 will also be squared. Centered in each end of the slat 16 is an opening 19, the depth and diameter being preferably determined by the thickness of the slat.

In conformity with the invention, it is intended to mount a shoe 21 on each end of the slat 16. These shoes are identical and of generally T-shape. The stem of the T consists of a channel 22, having a base wall 23 and side walls or flanges 24. The sides 24 are preferably of a lesser height than the thickness of the slat 16 adapted to be mounted in this channel. The base wall 23 is formed with a slot 26 which, when the end of the slat is mounted in the channel, registers with the slat opening 17. The cross portion of the shoe consists of an angle bar 27. This bar is permanently joined, along its lower or horizontal flange 28, to the end of the channel 22, the jointure being such that ends of flanges 24 abut the upright flange 29 of the bar. As shown in the drawings, the bar 27 is of a length such that, when in position on the cleat 14, it will have a considerable bearing surface along its flange 28 on said cleat and, of course, since flange 29 is of approximately the same length, said last flange will have a considerable bearing surface against the side rail 13.

Mounted in the end opening 19 is a coiled compression spring 31. This spring is of such length that it normally would project at least half its length beyond the end of the slat in which it is mounted. The exposed end of the spring bears against the flange 29 of the bar 27. The bolt 18 heretofore mentioned projects vertically through the slat 16 and the head 32 thereof may be countersunk into the top surface of the slat, or formed

with a slightly curved head, as shown. The shank of the bolt projects through the slot 26 and is fitted with a conventional washer and wing nut structure 33. The relationship of the slot 26, spring 31, and bolt 18 will be fully understood from the following description of the installation of the structure above described.

When it is desired to mount slats embodying the present invention in the frame of a bed, the shoes 21, carried by the slat ends, will be adjusted, with respect to said ends, from the position of Fig. 4 to that of Fig. 3. This adjustment, of course, compresses springs 31 and, in order to hold the springs in compressed position, the nuts 33 are tightened to prevent relative lengthwise movement of the slat 16 and channels 22. When the shoes have been thus located, the slat may be set into the bed frame between the side rails 13. Inasmuch as the slat is of a lesser length than the space between the side rails 13, the shoes 21, although resting on the cleats, will not, in all probability, contact said rails. Next, one of the wing nuts 33 is loosened and this releases spring 31, allowing it to extend the shoe 21 to an extent that the flange 29 of the bar 27 abuts the bed rail 13. The nut 33 on the shoe at the opposite end of the slat is also released to cause engagement of this shoe with the adjacent rail 13. Assuming that the springs 31 are of substantially uniform tension, it will be evident that the slat will be balanced between the side rails 13 and the shoes 21 will have pressure engagement with the side rails 13. The nuts 33 are now tightened and the slat and shoe structure is secured in place against displacement.

Although it is common practice to utilize three to five slats throughout the length of a bed or couch frame in order to provide adequate spring and mattress support, it is contemplated that the slat 16 may be of such width and thickness that only two will be necessary. In any event, the additional one, two, or three slats that may be required are mounted in the bed or couch frame in the manner above described. Upon completion of such mounting, it will be observed that due to the extensive bearing surface of each shoe with the side rails and the fact that the shoes are locked against any movement with respect to the slats, the bed or couch frame has been made absolutely rigid and will be so held in its true rectangular form regardless of any movement of the entire bed frame or of any use to which the bed may be put when spring and mattress are mounted thereon.

Reference is now more particularly had to Figs. 6 to 8 inclusive, wherein a modification of the structure above described is shown. Herein a slat unit, generally indicated by the numeral 34, is shown mounted in a bed or couch frame (see Fig. 6). In this instance, a pair of slats 37 are provided with shoe structures 38. Each of these structures includes an angle bar 39, to the ends of which are permanently attached channels 41. The channels in this modification are identical with the channels 22 heretofore described and, for purposes of the present illustration, the angle bars 39 may be of approximately the same length as the previously mentioned bars 27. Of course, in this instance the bar 39, by reason of its connection with corresponding ends of two of the slats 37, is urged into pressure engagement with the side rail 13 under considerably greater pressure than the bar 27, in view of the fact that there are two springs functioning for this purpose. From the showing of Fig. 6, it will be understood that the average bed or couch will be

fitted with two units 34 and, when these units have been installed in precisely the manner of installation of the single slat 16, it will be found that the frame of the bed or couch will be rigidly maintained in its true rectangular form. Of course, the pressure of the bars 39 of the dual shoes in this modification prevents displacement of the unit at all times.

Many beds and couches, prior to their being used for their intended purpose, are shown or displayed in sales rooms. Under these circumstances, it is contemplated not only to disclose the structure of the bed frame but the spring structure as well, and also enable elimination of the display of a mattress, since mattress covers become soiled under such conditions and would not readily be saleable. In other words, by raising the spring of a bed or couch to a height normally assumed by a mattress located on a spring, it is possible to not only display the spring but also display bedspreads and give the effect of a completely made bed. To accomplish this and at the same time utilize the structure of the invention, it is proposed to provide shoes 42 of the type shown in the other modifications of the drawings. The channels 43 of these shoes are identical with those previously described, and mount and secure either rail 16 or 31. The angle bar 44, however, is formed with a laterally offset top flange 46, this flange being an addition to the structure of the angle bars previously described. As may be seen in Fig. 9 of the drawings, flange 46 is intended to rest on the top edge of the rail 13. The vertical flange of the bar 44 abuts the rail in the same manner as the vertical flange of the other bars. When either single slats 16 and their attached shoes 21, or units 34, are provided with bars having the additional flange, they may be set in place on the rails substantially as heretofore described; that is, by allowing the shoes to be freely extended against the rails under compulsion of springs 31. When the slat units are thus located, the nuts 33 are turned down and the bed frame, with the slat structure in the plane of the top of the bed rails, is held rigid and capable of supporting a spring.

Although applicant has shown and described only two forms of shoes for mounting and securing slats in fixed relation to side rails of the frame of a bed or couch, and one variation in the structure of the shoes by which to locate

slats to a different height with respect to the rails, it will be understood that other modifications, particularly with respect to the proportions of the slats and shoes, may be made and are contemplated insofar as such modifications are within the spirit and scope of the annexed claim.

Having thus set forth my invention, what I claim as new and for which I desire protection by Letters Patent is:

In a structure having connected end and side rails forming a generally rectangular frame and having slats for bridging the space between said side rails; supporting means for the ends of said slats, said supporting means comprising a shoe that includes an elongated bar formed by integral right angle flanges, one flange of said bar being engageable with one of said side rails, a channel integral with and extending at right angles to the length of said bar and being substantially in the plane of the other of said bar flanges, said channel being proportioned to receive and seat a slat end in such intimacy as to require a slat to extend in the direction of the length of said channel and at right angles to said bar, means carried by said channel operable to secure the seated slat end against lengthwise movement in said channel, said bar being of such greater length than the length of said channel as to normally prevent displacement of a slat from a right angle relationship with respect to one of said side rails when one flange of said bar engages said one side rail throughout its length.
